WELL CEMENTING APPARATUS

Clarence E. Burt, Los Angeles, Calif., assignor
to Baker Oil Tools, Inc., Huntington Park,
Calif., a corporation of California

Application December 12, 1938; Serial No. 245,242.

7 Claims. (Cl. 166—9)

This invention relates to tools and equipment utilized during the drilling of oil wells, particularly those tools of the type described and claimed in my co-pending application entitled "Well cementing device," filed December 12, 1938, Ser. No. 245,241.

It is the principal object of my present invention to provide a simple and efficient apparatus for use in cementing operations in properly forming a cement plug in an open well bore a proper distance below the lower terminal of the well casing.

In practicing my invention, I provide a tubular member such as a casing shoe for attachment to the lower end of a well casing. I also provide a tail pipe or tube which is comparatively small in diameter with respect to the diameter of the well casing and which is slidably connected to the shoe by means of a connector means which also serves as a guide for the lower end of the casing. This tail pipe or tube may extend downwardly a considerable distance below the shoe and is provided with a nozzle at its lower end to enable forming of a comparatively long solid cement plug in the bore directly below the casing after the latter has been positioned. Due to the sliding connection described, the tail pipe may be maintained within the casing until the latter has been positioned in the bore and then projected downwardly from the lower end of the casing by means of fluid pressure.

One form which the invention may assume is exemplified in the following description and illustrated by way of example in the accompanying drawing, in which:

Fig. 1 is a view in central vertical section through an apparatus embodying the preferred form of my invention and showing it in the condition it assumes while the casing is run into the well bore.

Fig. 2 is a similar view but disclosing the tail pipe in projected position.

Referring more particularly to the accompanying drawing, 10 indicates a tubular member, such as a casing shoe, which is adapted to be connected to the lower end of a well casing, as in standard practice. Cast or otherwise secured into the casing shoe 10 is a cementitious plug 11, the lower end of which is rounded as at 12 so as to be guide-shaped and thereby guide the lower end of the casing past the joints and obstructions. Formed centrally within this concrete or cementitious plug 11 is a concentrically located guide bore 14 which extends longitudinally through the plug 11 to slidably receive a

tail pipe or tube 15. The upper end of this tube 15 is formed with an enlarged head 16 and its lower end is formed with a nozzle 17. The length of the tail pipe 15 may be such as desired or such as is necessary to form a cement plug of the desired length in the well bore below the casing.

It will be noticed that the plug 11 is formed with two annular recesses 18 to receive packing rubbers 19 so arranged as to prevent fluid flow between the bore 14 and the tail pipe 15 in either direction.

At the lower end of the tail pipe 15 is the nozzle 17. I have shown a whirler type of nozzle which is secured in the lower end of the imperforate tail pipe. This nozzle is formed with spirally arranged passageways 20 so that cement or other fluid discharged downwardly through the tail pipe will be caused to swirl as it is ejected. In cementing operations, this has a particular advantage in that it evenly distributes the cement slurry around the bore and prevents channeling of the cement so that a proper cement plug will be formed. This type of nozzle is described and claimed in my co-pending application above identified.

I prefer that the concrete plug 11, the tail pipe 15 and the nozzle 17 be formed of drillable material. For example, the connector means or plug 11 may be formed of concrete, Bakelite or drillable aluminum, if so desired, and I prefer that the tail pipe 15 be formed of a suitable aluminum alloy which is easily drilled up. The nozzle 17 may be formed of like material.

In operation of the device, it is constructed as illustrated and described and the casing is lowered into the well bore with the tail pipe in the withdrawn position as shown in Fig. 1. After the casing has been positioned, pump pressure exerts a downward force on the tail pipe causing it to project to operating position as shown in Fig. 2. At that time cement may be ejected downwardly through the casing and tail pipe and distributed in the bore to form a cement plug.

After the cementing operation is complete, a solid cementitious plug will be formed in the bore below and surrounding the casing shoe. It is desirable in some localities that this plug be solid for a distance at least fifteen feet below the casing and in such instances the tail pipe is of a length enabling this to be accomplished. The tail pipe 15 will be incorporated in this plug as it will be cemented solidly therein and likewise its interior will be filled with cement.

If it is desired to drill through the cement plug, the drill may readily advance through the casing shoe, drilling up the connecting member 11 and may advance further by drilling up the cement 5 and the tail pipe and the nozzle at the lower end of the latter.

By enabling the tail pipe to be withdrawn into the casing during the lowering thereof, danger of having the tail pipe bent or broken off during 10 this travel is obviated.

While I have shown the preferred form of my invention, it is to be understood that various changes may be made in its construction by those skilled in the art without departing from the 15 spirit of the invention as defined in the appended claims.

Having thus described my invention, what I claim and desire to secure by Letters Patent is:

1. In combination, a cylindrical member 20 adapted to be connected to the lower end of a well casing, an elongated tube of a diameter considerably less than the cylindrical member to extend coaxially from the lower end thereof, and means slidably connecting the cylindrical member and tube and closing the annular space between the exterior of the tube and the cylindrical member, said tube having an enlarged head disposed above said closure means and of a diameter appreciably less than that of the bore of said 30 member and said casing to permit free by-passing of fluid around said head in either axial direction, said means having a coaxial bore through which said tube extends into the casing above said means.

2. In combination, a cylindrical member 35 adapted to be connected to the lower end of a well casing, an elongated tube of a diameter considerably less than the cylindrical member to extend coaxially from the lower end thereof, and 40 means slidably connecting the cylindrical member and tube and closing the annular space between the exterior of the tube and the cylindrical member, said tube having an enlarged head disposed above said closure means and of a diameter appreciably less than that of the bore of said 45 member and said casing to permit free by-passing of fluid around said head in either axial direction, said means and said tube being formed of drillable material, said means having a coaxial 50 bore through which said tube extends into the casing above said means.

3. In combination, a cylindrical member 55 adapted to be connected to the lower end of a well casing, an elongated tube of a diameter considerably less than the cylindrical member to extend coaxially from the lower end thereof, and means slidably connecting the cylindrical member and tube and closing the annular space between the exterior of the tube and the cylindrical member, a whirler nozzle at the lower extremity 60 of said tube, said means having a coaxial bore through which said tube extends into the casing above said means.

4. In combination, a cylindrical member adapted to be connected to the lower end of a well casing, an elongated tube of a diameter considerably less than the cylindrical member, means slidably connecting the cylindrical member and tube to enable the tube to be withdrawn into the casing and projected therefrom by fluid pressure and closing the annular space between the exterior of the tube and the cylindrical member, and a nozzle at the lower end of the tube, said means having a coaxial bore through which said tube extends into the casing above said means.

5. In combination with a cylindrical member adapted to be connected to the lower end of a well casing, an elongated tail pipe of a diameter considerably less than the cylindrical member, a guide member secured to the cylindrical member and through which said tail pipe is slidably disposed, said tail pipe having an enlarged head disposed above said guide member and of a diameter appreciably less than that of the bore of said cylindrical member and said casing to permit free by-passing of fluid around said head in either axial direction, said guide member closing the annular space between the exterior of the tail pipe and the interior of the cylindrical member, said guide member having a coaxial bore through which said tail pipe extends into the casing above said member.

6. In combination with cylindrical member 30 adapted to be connected to the lower end of a well casing, an elongated tail pipe of a diameter considerably less than the cylindrical member, a guide member secured to the cylindrical member and through which said tail pipe slidably extends, 35 said guide member closing the annular space between the exterior of the tail pipe and the interior of the cylindrical member, a nozzle at the lower end of said tail pipe, said nozzle having a plurality of discharge passageways formed 40 downwardly therethrough, said passageways being spirally formed so as to tend to discharge the fluid in a whirling fashion, said guide member having a coaxial bore through which said tail pipe extends into the casing above said 45 member.

7. In combination, a casing shoe adapted to be secured to the lower end of a well casing, an elongated tail pipe of a diameter considerably less than the casing shoe, a concrete plug cast in said 50 casing shoe and having a guide-shaped nose extending from the lower end thereof, said tail pipe having an enlarged head disposed above said plug and of a diameter appreciably less than that of the bore of said casing shoe and said well casing 55 to permit free by-passing of fluid around said head in either axial direction, said plug having a coaxial bore through which the tail pipe slidably extends, and packing means between the bore and tail pipe, said tail pipe extending entirely through said bore and into the casing above 60 said plug.

CLARENCE E. BURT.
